BOLT CUTTER

Application filed July 10, 1928. Serial No. 291,618.

This invention relates to a cutter for severing bolts and other pieces of wire and metal rods.

The principal objects of the invention are to provide means for inserting removable steel cutting jaws on the cutter; to provide a configuration of said jaws which will securely hold them in exactly proper position; and to provide an improved pivot joint for reducing the friction. Other objects and advantages of the invention will appear hereinafter.

Reference is to be had to the accompanying drawings, in which

Fig. 1 is a side view of a bolt cutter constructed in accordance with this invention;

Fig. 2 is an end view of the pivot point taken at the position of the arrow 2 in Fig. 1;

Fig. 3 is a sectional view on the line 3—3 of Fig. 2;

Fig. 4 is an end view of the jaws on enlarged scale; and

Fig. 5 is a side view of the jaws looking in the opposite direction from that in which Fig. 1 is taken.

This bolt cutter is designed to be used in connection with the well-known design now on the market, in which a pair of handle levers 10 are pivoted together at 30 and provided with a pair of extensions 11 secured to them by screws 12 and 13 and which support pivot bolts 14 for the jaw levers 15. These jaw levers, as is customary, are pivoted on bolts 16 carried by cross pieces 17. The parts as so far described are all old and do not constitute a part of this invention except that we have selected them as being a convenient means for supporting and carrying the rest of the device.

The jaw levers 15 are provided ordinarily with cutting jaws. In accordance with the present invention these jaw levers are provided with notches 19 formed on a practically central plane and having undercut slanting surfaces 20 for a purpose to be described. The edges 21 of these jaw levers are also cut back on planes parallel with the surfaces 20.

A pair of steel jaws 22 are mounted on these jaw-levers. By having these steel jaws made separate and secured by bolts 23, they

are readily removable and replaceable; they can be sharpened conveniently, and if notched or broken either one of them can be replaced either with or without the other. Each jaw 22 is provided with a cutting edge 24 located between the planes of the two slanting surfaces 20 and 21. Thus pressure on the cutting edge is transmitted back to said slanting surfaces and tends to seat the jaw more firmly thereon, and does not tend to rock it about any part of its support. The main body 22 of each jaw is perforated to receive the bolt 23, and has two surfaces fitting the surfaces 20 and 21 and slanting backwardly from the cutting edge. This constitutes a very firm arrangement and the tightening up of the bolts 23 forces the jaws into a rigid position on the ends of the jaw levers. Owing to the parallel slant of the surfaces 20 and 21 the steel jaws cannot become slightly tilted after use and, in assembling and replacing, they necessarily assume the correct position. Furthermore even if the bolts get loose the tool can still be used temporarily for cutting purposes on account of the parallel slanting surfaces on which they are supported.

In order to make the whole device operate more easily, the pivot bolt 30 on which the two handle levers 10 are pivoted, is provided with a ball or roller bearing 31 having a casing 32 which is held by the two arms 33 extending from the handle levers 10. These two arms 33 are formed at their ends as circular hubs, one of which is located at the center and the other of which is bifurcated and surrounds it. The anti-friction bearing 31 is located to surround the bolt 30 and reduces the friction on both of the arms 33. With such a heavy tool this ball bearing constitutes an improved feature because the friction at this point has been excessive in makes of this tool on the market. It reduces the liability of injuring or breaking the bolt when cutting heavy stock.

Although we have illustrated and described only one form of the invention, we are aware of the fact that changes can be made therein by any person skilled in the art without departing from the scope of the invention as expressed in the claims.

Therefore, we do not wish to be limited to the exact form shown, but what we do claim is:—

1. In a bolt cutter, the combination with a pair of hand levers and a pair of jaw levers pivoted together, said jaw levers having a notch in the inner side of each with a backwardly slanting or undercut rear edge and a plane wall parallel to the line of thrust and a forward edge in advance of the same slanting in a substantially parallel direction but off-set laterally therefrom, thus forming a Z-shaped outline, of a pair of removable steel jaws secured thereto and having surfaces fitting said plane and slanting surfaces, whereby the steel jaws will have a bearing on both of said slanting surfaces, and bolts for securing the steel jaws in position on the said jaws, whereby even if the bolts get loose the jaws will tend to remain in position.

2. In a bolt cutter, the combination with a pair of hand levers and a leverage system having a pair of jaws at the end, each jaw being provided with a notch on one side having a backwardly slanting or undercut rear edge and a plane wall parallel to the line of thrust and a forward edge in advance of the same but in a different plane slanting in a substantially parallel direction, of a removable steel jaw secured thereto and having surfaces fitting said plane and slanting surfaces, the cutting edge being located with its median line in a plane between the planes of said slanting surfaces, and bolts for securing the steel jaws in position on the said jaws.

In testimony whereof we have hereunto affixed our signatures.

HENRY P. BLUMENAUER.
